UNITED STATES PATENT OFFICE

CARL WILHELM APPELBERG, OF STOCKHOLM, SWEDEN, ASSIGNEE TO AKTIEBOLAGET
BIRKA REGULATOR, OF STOCKHOLM, SWEDEN, A COMPANY OF SWEDEN

THERMOSTAT SWITCH

Application filed March 10, 1931, Serial No. 521,572, and in Sweden March 27, 1930.

The present invention relates to such thermostat switches in which the separation and bringing together of the contacts is effected through the deformation of bimetallic members under the influence of temperature fluctuations. A primary object of the invention is to reduce as far as possible the dimensions of the thermostat while maintaining a desired magnitude of the contact movement for a given temperature variation, which may be accomplished according to the invention without complicating the apparatus or making it more expensive. A reduction of the dimensions is desired especially in thermostat switches of the kind which for the purpose of increasing the efficiency of the thermostat are enclosed in evacuated receptacles or in receptacles filled with an inert gas.

According to the invention the portion of the thermostat deformable through temperature variations is composed of a plurality of coaxially disposed bimetallic plates or disks thread on to a rod and bearing with like sides against each other, said disks assuming upon a change in temperature a more or less cup shaped form in such a way that the deformation movements of the disks are added and together effect a contact movement in the longitudinal direction of the rod.

The invention is particularly applicable to such thermostat switches in which the contact is formed by coaxial metal rods which are axially displaceable in relation to each other and the two adjacent ends of which normally bear against each other. In this type of thermostat the bimetallic disks are preferably thread on to one of the contact rods, whereby the heat sensitive element is obtained in the simplest possible manner and at the same time in a particularly efficient form.

The invention will be more closely described with reference to the accompanying drawing showing two different embodiments of the same. Figure 1 is an axial section through the thermostat switch according to one embodiment of the invention, the switch being shown in closed condition. Figure 2 shows the same section after the contacts

have been separated through heating. Figure 3 is an end view of the switch shown in Figure 1. Figures 4 and 5 show in section and on a larger scale the bimetallic disks in normal and in deformed condition respectively. Figures 6 and 7 are axial sections through the thermostat switch according to the second embodiment. Figure 8 shows in section and on a larger scale the system of bimetallic disks serving to effect the closing of the contacts of the embodiment shown in Figures 6 and 7.

In the embodiment illustrated in Figures 1 to 3 the thermostat contact is enclosed in a cylindrical receptacle 1 preferably of insulating material. The thermostat contact is formed by two coaxial rods 2, 3, one of which, 2, is screwed into a metal sleeve 4 disposed in one end wall of the cylindrical receptacle whereas the opposite rod 3 is slidably supported in the other end wall. The two adjacent ends of the rods are normally held in contact with each other by a helical spring 5 inserted between a collar on the rod 3 and the end wall of the receptacle. On to the portion of the rod 3 projecting outside the receptacle are thread a plurality of bimetallic plates or disks 6 between a shoulder 7 on the end wall of the receptacle and a nut 8 screwed on to the outer end of the rod 3. Only four such disks are illustrated on the drawing but any number may be chosen in accordance with the desired magnitude of contact movement. One external conductor 9 of the switch is connected to the sleeve 4 and the other 10 is pressed between the nut 8 and an appertaining lock nut 8'.

Each of the bimetallic disks 6 is composed of two metal layers *a*, *b* having different coefficients of expansion. The disks 6 are disposed together in a row in such a way that the first one, the third, the fifth etc. reckoned from the receptacle turn the layer *a* having the larger coefficient of expansion toward the receptacle whereas the other disks are turned the opposite way. Consequently two and two of the disks bear against each other with their layers *b* whereas the different couples of disks bear against each other with the layers *a* (Figures 4 and 5).

The bimetallic disks 6 are made in such a way that they are substantially plane at normal temperature, as will be seen from Figures 1 and 4. When heated the layers ⁶ expand more than the layers ⁷ whereby the disks become cup-shaped, the left disk of each couple of disks turning the convex side, the other disk on the other hand turning the concave side toward the receptacle 1. In ¹⁰ deformed condition the disks bear against each other near their centers and at their circumference respectively, as shown in Figure 5, and the column formed by the disks will thus when heated extend in an axial direction ¹⁵ pressing the nut 8 outwards, whereby the contact is broken. If the disk at normal temperature were squeezed tightly together between the end wall 7 and the nut 8 the movement of the contact would obviously be equal ²⁰ to the sum of the bulgings of the different bimetallic disks. Generally, however, small clearance spaces should exist at normal temperature, the total magnitude of which spaces may be adjusted by means of the nut 8 whereby the limit temperature at which the contact is broken may be regulated. When the bimetallic plates, upon a decrease in temperature, return to their normal plane condition ²⁵ the rod 3 is again brought into contact with the other rod 2 under the action of the helical spring 5.

If desired annular washers may be disposed between the different bimetallic plates, either closely surrounding the rod 3 or inserted between the plates at their circumference.

In the embodiment according to Figures 6 and 7 the helical spring 5 is dispensed with. The restoration of the rod 3 to contact position is here brought about by means of a system ⁴⁰ of bimetallic disks 11, said system being similar to the disk system 6 but adapted to operate in an opposite manner, the disks 11 being normally cup-shaped but approaching the plane form at rising temperature. The ⁴⁵ disks 11 are thread on to the rod between the locknut 8' appertaining to the nut 8 and a fixed support 12 which through arms 13 is secured to the receptacle 1. When heated the disk system 6 expands as in the former ⁵⁰ case whereas the system 11 is contracted in an axial direction, and consequently the nut 8 will, as in the previous embodiment, be pressed outwards. At a subsequent cooling the rod 3 is forced back to its contacting position through the expansion of the column 11 ⁵⁵ and the contraction of the column 6.

The thermostat in its entirety may be enclosed in a glass tube 14 preferably disposed concentrically about the former which glass tube ⁶⁰ preferably is evacuated or filled with an indifferent gas. The thermostat may be adapted to be actuated either under the influence of temperature changes in the surroundings or by means of a special heating ⁶⁵ winding which latter may be disposed outside

or inside the glass tube, in the latter case preferably on a supporting cylinder secured to the receptacle 1 and enveloping the bimetallic plates.

Instead of adapting the bimetallic disks ⁷⁰ to directly actuate the movable contact member the parts may be disposed in such a manner that the sum of the deformations of the disks is transmitted to said contact member through the intermedium of a gearing, for example a lever, a cam gearing or the like. ⁷⁵

I claim:

1. A thermostat electrical switch disposed in a receptacle and comprising a contact operating rod longitudinally slidable in said receptacle, a plurality of bimetallic heat sensitive plates slidably thrust on said rod with like plate sides facing each other, and means for transferring reciprocating heat deformation movements of said plates to said rod. ⁸⁰ ⁸⁵

2. A thermostat electrical switch disposed in a receptacle and comprising a stationary rod shaped contact member mounted in said receptacle, a reciprocable rod shaped contact member slidably mounted in said receptacle coaxially with and in opposition to said stationary member, a plurality of bimetallic heat sensitive plates slidably thrust on said reciprocable member with like plate sides facing each other, and means for transferring reciprocating heat deformation movements of said plates to said reciprocable member. ⁹⁰ ⁹⁵

3. A thermostat electrical switch disposed in a receptacle and comprising a contact operating rod longitudinally slidable in said receptacle, a system expansive to heat and a system contractive to heat, each system having a plurality of bimetallic plates slidably thrust on said rod with like plate sides facing each other, and means for transferring heat expansive and heat contractive movements of said two systems to said rod to reciprocate same. ¹⁰⁰ ¹⁰⁵

4. A thermostat electrical switch disposed in a receptacle and comprising a stationary rod shaped contact member mounted in said receptacle, a reciprocable rod shaped contact member slidably mounted in said receptacle coaxially with and in opposition to said stationary member, a system expansive to heat and a system contractive to heat, each system having a plurality of bimetallic plates slidably thrust on said reciprocable member with like plate sides facing each other, and means for positively transferring heat expansive and heat contractive movements of said two systems to said reciprocable member to reciprocate same. ¹¹⁰ ¹¹⁵ ¹²⁰

5. A thermostat electrical switch disposed in a receptacle and comprising a contact operating rod longitudinally slidable in said receptacle, a system expansive to heat having a plurality of normally flat bimetallic plates slidably thrust on said rod with like plate ¹²⁵ ¹³⁰

sides facing each other, a system contractive to heat having a plurality of normally cup shaped bimetallic plates slidably thrust on said rod with like plate sides facing each other, and means for transferring heat expansive and heat contractive movements of said two systems to said rod to reciprocate same.

6. A thermostat electrical switch disposed in a receptacle and comprising a stationary rod shaped contact member mounted in said receptacle, a reciprocable rod shaped contact member slidably mounted in said receptacle coaxially with and in opposition to said stationary member, a system expansive to heat having a plurality of normally flat bimetallic plates slidably thrust on said reciprocable member with like plate sides facing each other, a system contractive to heat having a plurality of normally cup shaped bimetallic plates slidably thrust on said reciprocable member with like plate sides facing each other, and means for positively transferring heat expansive and heat contractive movements of said two systems to said reciprocable member to reciprocate same.

In testimony whereof I affix my signature.
CARL WILHELM APPELBERG.
